[57] CLAIM

The ornamental design for “pump assembly for whirlpool bath systems”, as shown and described.

DESCRIPTION

FIG. 1 is a three-dimensional view of the present invention; FIG. 2 is a front view of the invention;

FIG. 3 is a rear view thereof;

FIG. 4 is a bottom view thereof;

FIG. 5 is a top view thereof;

FIG. 6 is a left-side view thereof; and,

FIG. 7 is a right-side view thereof.

The broken line showing of a pump housing, in FIG. 1, is for illustrative purposes only and forms no part of the claimed design.
